Primary Examiner — Rhea Shields*Assistant Examiner* — Ikeadi M Ndukwu(74) *Attorney, Agent, or Firm* — FITCH, EVEN, TABIN & FLANNERY, LLP(57) **CLAIM**

I claim the ornamental design for a tubular reactor, as shown and described.

DESCRIPTION

FIG. 1 is a front, top and left side perspective view of a tubular reactor, showing my new design.

FIG. 2 is a front elevational view thereof;

FIG. 3 is a right side elevational view thereof;

FIG. 4 is a left side elevational view thereof;

FIG. 5 is a rear elevational view thereof;

FIG. 6 is a top plan view thereof;

FIG. 7 is a bottom plan view thereof;

FIG. 8 is a cross-sectional view taken along line 8-8 in FIG. 2 thereof; and,

FIG. 9 is a cross-sectional view taken along line 9-9 in FIG. 4.

1 Claim, 9 Drawing Sheets(56)
